UNITED STATES PATENT OFFICE.

CHARLES M. ALLEY, OF SAN FRANCISCO, CALIFORNIA.

CONCRETE WALL CONSTRUCTION.

Application filed December 22, 1925. Serial No. 77,044.

This invention relates to concrete wall construction, and particularly to movable forms as used for pouring such walls.

The principal objects of the present invention are to effect certain improvements over the forms shown in my Patent No. 1,550,051, issued August 18, 1925, whereby the rising wall is more easily maintained perfectly vertical and the forms may be somewhat more easily assembled, together with improved mold and aligning connections making the use of my system of forms more practicable.

In the drawings hereto the improvements over my earlier construction are shown, together with sufficient detail of the earlier structure so as to make them understandable.

Figure 1 is a perspective view of a wall being erected with my improved forms showing substantially all the features of importance and with one of the hollow core molds raised vertically out of the wall forms.

Figure 2 is an enlarged vertical cross section of a portion of the wall to better show the relation of the forms to the clamping and aligning devices.

Figure 3 is an enlarged perspective view of one of the form aligning clamps mounted on the vertical wall aligning bar.

Figure 4 is an enlarged perspective view of one of the track hangers secured to the upper end of the wall aligning bar.

Figure 5 is a perspective view of one of the straps which space the sides of the wall forms and support the cores which form the wall hollows.

Figure 6 is a fragmentary perspective view of a concrete wall between forms held together by my improved cleats and tie wires.

Figure 7 is a longitudinal section of the wall forms showing my improved cleats and tie wires for holding the walls against outward pressure.

Figure 8 is an elevational view of a cleat, to the upper end of which a similar cleat is fitted, the upper cleat being shown as a fragment, and

Figures 9 and 10 are respectively sections taken on lines 9-9 and 10-10 of Figure 8.

Briefly explained the invention differs chiefly from my copending application showing a method of building concrete walls in which the wall forms were successively aligned upward against a bar hanging from an elevated track, in providing a double

track for the bar, one above the proposed wall and the other at the base or ascending surface with the vertical aligning bars held vertically at all times on these two tracks independent of the rising wall so as not to be influenced by it and thus avoid an incremental misalignment of the wall toward one or both sides, as possible with my earlier system if the forms were not perfectly cleaned before clamping to the ascending wall, or not clamped tightly enough thereagainst.

Other improvements consist in the details of the structure.

In Figure 1 a concrete wall in process of construction near the corner of the building is shown. The finished portion of the wall is designated 1, while arranged along its upper edge are two rows of my wall forms 2, some with and some without cores 3 in position, and some being filled with concrete 4 from a spout 5, others entirely filled as at 6, and still others where the concrete has set as at 7 and the cores have been removed showing the hollow wall spaces 8.

At each corner of the building are arranged vertical forms comprising inner and outer right angle boards 9 and 10 spaced by taper bolts 11, while the main wall forms comprise each a pair of boards 2 also spaced with taper bolts 11 as similarly shown in my copending application referred to, and also by upper straps 12 though in this case unsecured to the upper edges of the form boards.

The straps 12 as more clearly shown in Figure 5 are formed with several lugs or downward projecting pieces 12' adapted to simply be positioned over the form sides as indicated in Figures 1 and 2 so as to hold the form sides rigidly against inward or outward deflection. The two inner lugs not in contact with the form sides are for use with narrower wall construction wherein the form sides are to be held closer together, thus one set of straps is suitable for spacing the form sides for several thicknesses of walls.

At the outsides of the boards 2 are vertical cleats 13 preferably cut at an angle at the ends so as to project from the upper form a few inches over the side of the lower form.

In arranging a row of these forms along a wall being built they are first supported on the upper edge of the foundation forms 14 (see Figure 2) and as the wall is built each new row of forms is supported on the

upper edge of the row beneath, always allowing the row in which the wall is cast to remain until the new row is secured in position above it.

- 5 The succeeding rows of wall forms are vertically aligned by means of vertical bars 15 preferably channels with return edges 15' as more clearly shown in Figure 3, and which bars are adjustable along a pair of 10 horizontal tracks 16 and 17 aligned vertically over one another and to which tracks the bars are supported by hook hangers 18 so that they may be freely placed on the tracks or adjusted therealong.
- 15 The tracks 16 and 17 are carried on the upright members 19 of a scaffold 20 first built along one side (preferably the inside) 20 of the wall before commencing erection and if only a one story wall is to be built the bars 15 may be long enough and the tracks 16 and 17 spaced sufficiently to handle the job without shifting of the tracks, but if a wall several stories high is to be built the tracks may be elevated from time to time.
- 25 In the drawing one aligning bar 15 only is shown to avoid confusion, though it is the intention to use any number of them along the sides of the wall forms to accurately align them upwardly as each new row is positioned.

These bars are provided with sleeves as shown at 21 adjustable up and down the channel bar 15 by means of a clamp screw 22, extending between the return edges of 30 the channel and engaging a sliding nut 23 lying within the channel. The sleeves have a laterally extending arm 24 with downwardly turned lugs 25 thereon adapted to be positioned over the near edge of a form so as to hold it a definite distance from the vertical bar 15, it being found sufficient to have the arm engage the upper edge of the form only as the lower edges are aligned over the similarly aligned edges of the lower 40 row of forms.

45 By the arrangement described the ascending forms are aligned vertically by rigid bars always held in perfect vertical position on tracks at the upper and lower ends of the bars and the lower end independent of the wall, thereby preventing any gradual displacement of the wall from gradually displacing the lower ends of the vertical bars 15 as was possible in my former construction as mentioned.

50 In forming hollow walls the cores 3 attached in groups to a concrete-diverting gable roof plate 3' are supported on the straps 12 as in my copending application, and the taper spacing bolts 11 are positioned about a third upward from the lower edges of the forms so that when the loose straps 12 are removed the upper edges of the forms will not spread to any extent and when a 60 new row of forms is placed above the edges

will easily close to exact position upon driving the keys 11' into the taper bolts.

It should be observed that since the straps 12 are not secured to the opposite form sides they may be freely lifted therefrom so that a workman in placing or removing the forms need only lift single sides and not the two attached sides, as before, thus reducing the weight lifted to one half and providing for easy transportation and stacking of the forms in a minimum space.

70 The upper ends of the corner forms 9 and 10 are held by boards 26 and 27 extending from the track or scaffold upright 20' and notched to space the upright form boards 80 as shown in Figure 1.

75 In pouring the concrete advantage is taken of the upper track 17 as a support for a rolling hopper 28 having a depending spout 5 so that the hopper may be rolled 85 along the track and the spout will always come directly over the wall forms to be filled.

80 This hopper 20 is provided with two sets of rollers 29 and 29' and is shown hanging from the track on the set of rollers 29, the other set being used when reversing the direction of the spout or when the track is on the other side of the wall.

85 In carrying out my improved arrangement using the two tracks, it is desirable for simplicity's sake that the tracks be vertically aligned on one side of the wall by being nailed against common uprights, but this is not absolutely necessary as the tracks may be offset so long as they are parallel to one another, it simply being necessary to make the offset of the upper and lower bar hook 18 to correspond, and the hooks may also be vertically adjustable along the open side of the channel bar as shown in Figure 4 where in the hooks are clamped to the return edges of the bar by a bolt 30 engaging a sliding nut 31 within the channel.

90 Referring now to Figures 6 to 10 inclusive, the improved cleat 39 shown in Figure 8 comprises a rib 40 having spaced walls 41 and 42 from which project respectively, coplanar flanges 43 and 44. The flanges 43 and 44 are provided with apertures 45 through which nails may extend to fasten the cleats to the wall forms 2. The rib 40, as shown in Figure 8 extends below the flanges 43 and 44, this extended portion of the rib being narrower than the main portion of the rib. The rib 40 also extends above the upper ends of the flanges 43 and 44, and is provided with a slot 48 at its upper end. A cleat 50 is shown as cooperating with the cleat 39. The cleat 50 is of the same construction as the cleat 39. The upper end of the rib 40 of the cleat 39 fits over the reduced lower end portion of the cleat 50. As shown in Figure 7 the rib which I have constructed is made arcuate as indicated by the numeral 52 100

at the slotted end, both sides 41 and 42 being arcuated. As shown in Figure 8, the tie wires 55 and 56 are looped around the ribs of the cleats, the wire 55 being disposed between the adjacent flanges of the cleats 39 and 50, while the tie wire 56 is looped around the reduced portion 47 of the rib 40 just below the flanges 43 and 44. These tie wires extend through the wall forms 2 and around the ribs, and another pair of cleats identical with the pair of cleats 39 and 50. It will thus be readily seen that by tightening the wires 55 and 56, the cleats may be held to the wall forms. The tie wires 55 and 56 are provided respectively with loops 58 and 59 by winding wires 60 and 61 respectively around them. These loops are for the purpose of centering the core hereinbefore described. When it is desired to remove the lower wall forms, the lower tie wire 56 is cut and the forms may then be removed, this removal being facilitated by the arcuate edges 52 of the rib of the cleat and the provision of the slot 48 in the rib.

I claim:

1. In wall molding apparatus, a pair of guides parallel with the proposed wall and supported one above the other, and a device supported by and extending vertically from one guide to the other adapted for vertically aligning the wall as it is built upward.

2. In wall molding apparatus with movable wall forms, an aligning bar vertically supported adjacent the proposed wall independent thereof, means projecting from said bar adapted for gripping both sides of a side board of the wall form for spacing the board from the bar.

3. In wall molding apparatus, a pair of tracks parallel with the proposed wall supported one above the other, and a substantially rigid bar extending vertically from one track to the other and adjustable therewith for aligning the wall vertically therewith as the wall is built.

4. In wall molding apparatus with movable forms, an elevated track supported parallel with the proposed wall, a channel bar vertically supported from the track and a device slidably supported in the channel of the bar adapted for aligning the wall forms with the bar.

5. In wall molding apparatus with movable wall forms, a guide elevated above the wall adapted for aligning the wall forms parallel therewith, and a concrete hopper movable along said guide provided with a spout adapted to discharge into a row of said forms for casting the wall as the hopper is moved along.

6. In wall molding apparatus, a scaffold at one side of the wall, a pair of tracks carried by the scaffold, one of said tracks being elevated above the other and both being parallel with the proposed wall, an aligning bar extending across both tracks vertically supported thereby, wall forms for casting the wall, and means extending from the bar for aligning the forms vertically and parallel to the tracks.

7. A cleat comprising a rib, coplanar flanges extending laterally from said rib, said rib being longer at both ends than said flanges.

8. In false structure, spaced walls, a pair of cleats on the outside of each of said walls, each cleat comprising a rib having a notch at one end and being thinner at its other end than at its notched end, the notched end of each rib of each lower cleat enclosing the thinner end of the cleat with which it is paired.

9. In false structure, spaced walls, a pair of cleats on the outside of each of said walls, each cleat comprising a rib having a notch at one end and being thinner at its other end than at its notched end, the notched end of each rib of each lower cleat enclosing the thinner end of the cleat with which it is paired, and wires looped around said cleats and having a loop between said walls.

10. In false structure, spaced walls, a pair of cleats on the outside of each of said walls, each cleat comprising a rib having a notch at one end and being thinner at its other end than at its notched end, the notched end of each rib of each lower cleat enclosing the thinner end of the cleat with which it is paired, and wires looped around said cleats.

11. In false structure, spaced walls, a pair of cleats on the outside of each of said walls, each cleat comprising a rib having a notch at one end and being thinner at its other end than at its notched end, the notched end of each rib of each lower cleat enclosing the thinner end of the cleat with which it is paired, and a wire looped around opposing pairs of cleats between the cleats of each pair.

12. A cleat comprising a rib, coplanar flanges extending laterally from said rib, said rib being longer at both ends than said flanges, and having a notch at one end.

13. A cleat comprising a rib, coplanar flanges extending laterally from said rib, said rib being longer at both ends than said flanges and having a notch at one end and being thinner at its other end than at its notched end.

CHARLES M. ALLEY.
